CLAIM

The ornamental design for a shoe outsole, as shown and described.

DESCRIPTION

FIG. 1 is a front perspective view of a shoe outsole showing my new design;

FIG. 2 is a bottom view thereof;

FIG. 3 is a rear perspective view thereof; and,

FIG. 4 is an enlarged view of FIG. 1 with unclaimed subject matter omitted.

The photographic area is claimed. The lack of a line immediately adjacent to the photographic area indicates a claimed edge of the design. The 32 regions within the photographic area that are circumscribed by claimed edges of the design form no part of the claimed design. The broken lines showing the remainder of the shoe represent unclaimed subject matter and form no part of the claimed design.
